(57) **CLAIM**

The ornamental design for a wire drawer, as shown and described.

DESCRIPTION

FIG. 1 is a perspective view of a wire drawer, in a closed position, according to my new design;

FIG. 2 is a top plan view thereof;

FIG. 3 is a front elevational view thereof;

FIG. 4 is a side elevational view thereof, the opposite side being a mirror image;

FIG. 5 is a rear elevational view thereof;

FIG. 6 is a bottom plan view thereof; and,

FIG. 7 is a perspective view of the wire drawer, in an open position.
